UNITED STATES PATENT OFFICE.

HOWARD B. EYNON, OF LAKEWOOD, OHIO, ASSIGNOR TO NATIONAL CARBON COMPANY, INC., A CORPORATION OF NEW YORK.

ARC-LAMP ELECTRODE.

Application filed June 11, 1919. Serial No. 303,301.

To all whom it may concern:

Be it known that I, HOWARD B. EYNON, a citizen of the United States, residing at Lakewood, in the county of Cuyahoga and 5 State of Ohio, have invented a certain new and useful Improvement in Arc-Lamp Electrodes, of which the following is a full, clear, and exact description.

This invention relates to an improvement 10 in arc lamp electrodes, and particularly to negative electrodes especially adapted for use in projection apparatus.

One of the most important requirements 15 which must be fulfilled for this type of service is arc steadiness and my invention relates to, and especially discusses an electrode structure which satisfies this particular requirement.

I have found that the arc has a very 20 strong tendency to spring from the hottest part of a negative electrode and to remain there. I have found this to be especially true in the case of pure carbon electrodes or with electrodes in which no flaming ingredient is 25 present in close proximity to the portion of the electrode from which the arc springs. Although the same is true of electrodes containing small amounts of flaming material to a limited extent, the presence of flaming 30 material is undesirable because it reduces the temperature of the arc stream and the intrinsic brilliancy.

A preferred embodiment of the invention is illustrated in the accompanying drawing, 35 which shows a vertical section through the improved electrode.

Referring to the drawing, reference character 1 designates an outer shell preferably of pure carbon. The shell after baking is

provided with a core 2 consisting of carbon 40 flour mixed with a carbonaceous binder, such as a mixture of tar and benzol. After coring the article is dried or baked to set the binder. This results in a practically pure carbon article having a shell of dense carbon 45 and a central core of less dense and relatively porous carbon. When such an electrode is used in combination with a suitable positive, the arc will tend to spring from the central core during burning because 50 when the arc springs therefrom the core does not conduct heat to the shell readily. The spot from which the arc springs therefore tends to have a higher temperature for the reason given. On account of its central 55 location there is also a greater tendency for the arc to spring from the core than from the surrounding shell.

Although I have set forth what I believe is a reasonable explanation of the 60 steadiness of the electrodes, it must be understood that my invention is not necessarily limited thereto.

Having described my invention, what I 65 claim is:—

A negative electrode having a body portion consisting entirely of carbon, said body portion comprising a relatively dense and substantially pure carbon shell, and a core for said shell consisting of a relatively less 70 dense filler of carbonaceous material having a carbonaceous binder incorporated therewith, such filler being a good electrical conductor and a poor conductor of heat.

In testimony whereof, I hereunto affix my 75 signature.

HOWARD B. EYNON.
